STEAM HEATING SYSTEM

Elmer Paul Harrison, Chicago, Ill., assignor to
 Reconstruction Finance Corporation, Chicago,
 Ill., a corporation of the United States

Application December 23, 1946, Serial No. 717,951

8 Claims. (Cl. 237—67)

1

My invention relates to devices and processes employing steam, or the like, for the heat treatment of materials and for other purposes. While the invention is applicable to steam systems in general and may be used with various types of heat exchangers, the invention is of special utility for steam systems employed in the heat treatment of traveling material, for example, steam systems used in the manufacture of paper. The invention will be described as embodied in apparatus for the manufacture of paper for the purpose of disclosure and to teach, by way of example, how the invention may be applied wherever useful.

The advantage of releasing steam from the return side of a steam system for the promotion of flow velocity therethrough when the system is properly designed for velocity response is set forth in the Harrison et al. Patent No. 2,366,332, issued January 2, 1945, entitled Heat exchange system. The advantages of releasing the steam intermittently from the return side of the system to cause pulsating operation of the heat exchangers in the system for attacking gas and condensate films in the heat exchangers are set forth at length in the copending Harrison et al. application entitled Steam heating apparatus and method, Serial Number 713,774, filed on or about December 3, 1946. Both of these Harrison disclosures are included in the present disclosure by reference in so far as consistent therewith.

There is a great economic advantage in utilizing the released steam for some useful purpose, that is to say, for meeting some demand outside of the system, but usually it is a problem to match the requirement for the flow-promoting release of steam on the part of the system with the steam requirement on the part of the outside demand, especially when one or the other of these two requirements is variable. Thus, varying the release of steam from a steam system to meet a change in magnitude of the outside demand may result in lowering the efficiency of the steam system, and, conversely, changing the amount of steam released for the purpose of meeting a change in the operating conditions of the system itself may result in either deficiency of steam supply or wasteful excess of steam supply with respect to the outside demand.

Another problem that arises is the reconciling of pulsating-creating intermittent release of steam with the requirement to supply steam in a steady stream to satisfy a particular outside de-

mand. For example, the outside demand may be the steam requirement of steam showers or sprayers for moistening a traveling web of paper. Such a shower should operate in a steady, continuous manner even though supplied with steam that is released only intermittently from the return side of the steam heating system.

Important objects of the present invention are to meet the above-mentioned problems. In general these objects are attained by coupling with a steam heating system an outside demand, preferably a demand for more steam than need be released for the purpose of velocity promotion in the heating system, and by supplying a portion of that demand from the high pressure side of the system. In such an arrangement the optimum volume of steam release for flow promotion in the heating system may be utilized to meet a fraction of the outside demand, and the rest of the outside demand may be satisfied with live steam from the high pressure side of the system. It is contemplated that the ratio between these two supply components for the outside demand will be variable, so that, on the one hand, the amount of steam released for flow promotion may be varied without affecting the total quantity of steam supplied to meet the outside demand, and, on the other hand, the total quantity of steam released may be varied to follow a change in the outside demand without substantially varying the amount of steam released from the low pressure side of the system. Thus the heating system will supply the steam to satisfy the outside demand but, nevertheless, the total amount of steam supplied to the outside demand and the amount of steam released from the return side of the heating system may be varied independently.

The invention is further characterized by the use of a surge tank to smooth out flow variations where desirable, so that intermittently released steam or variably released steam may be utilized in substantially the same manner as steam supplied from a constant source.

In one practice of the invention a special object is to utilize the high pressure steam release to promote the release of steam on the low pressure side of the system, preferably in a pulsating manner.

A further object of the invention is to provide an exceptionally flexible system in the sense that the system is adjustable in various important respects, and in the further sense that the system is adaptable to various modes of operation.

The above and other objects and advantages of the invention will be apparent in the detailed description to follow, taken with the accompanying drawings.

In the drawings, which are to be considered as merely illustrative:

Fig. 1 is a diagram showing the essential elements of a preferred embodiment of my invention; and

Fig. 2 is a sectional view of an injector arrangement employed in the preferred embodiment.

The steam heating system represented diagrammatically in Fig. 1 includes a boiler 10, a high pressure steam header 11 supplied with live steam by the boiler, a return header 12 on the lower pressure side of the system, and a receiver 13 to collect condensate from the return header 12. The boiler 10 is supplied with water as required by a boiler pump 15, the boiler pump being connected on its intake side with the receiver 13 by a pipe 16, and being connected on its output side with the boiler by a pipe 17. New water for the system is supplied to receiver 13 as required through a pipe line 18.

The steam system represented by Fig. 1 has a plurality of heat exchangers, in this instance a plurality of drier rolls or cylinders such as used in manufacturing paper. The drawing being diagrammatic and being greatly simplified shows only twelve drier cylinders, there being six drier cylinders 19 in a high pressure bank A and six drier cylinders in a low pressure bank B. Actually paper making machinery is, of course, more elaborate than indicated by Fig. 1.

The various drier cylinders 19 of bank A are fed by individual supply pipes 21 from the steam header 11 and condensate and steam released therefrom to individual discharge pipes 22, all of the discharge pipes 22 communicating with a common return line 23.

In accord with a well known practice each of the discharge pipes 22 is provided with a restriction or orifice fitting 25, that is to say, a fitting or means providing a restriction to retard the flow of steam and condensate from the corresponding drier cylinder to the return line 23. Such an orifice member prevents "short circuiting" or such excessive flow through a drier cylinder as would unduly lower the pressure differential between the steam header 11 and the return line 23. In the particular arrangement shown steam and condensate from the return line 23 is conducted through a pipe 26 to a steam separator or receiver 27 which retains the condensate but releases the steam to a second low pressure steam header 28.

The drier cylinders 20 of the second bank B have individual supply pipes 30 branching from the low pressure steam header 28, and have individual discharge pipes 31 that lead to a common return line 32. Each of the discharge pipes 31 is shown equipped with an orifice fitting 25. Steam and condensate from the second return line 32 is conducted through a pipe 33 to a second steam separator or receiver 35. Condensate is retained by the receiver 35, but any steam therein may escape through a low pressure steam pipe 36.

Each of the two steam separators or receivers 27 and 35, respectively is provided with a valve 37 controlled by a float 38 so that accumulated condensate may be periodically released from the receiver to a pipe 40 leading to the return header 12.

The steam pipe 36 is provided with a suitable valve 41 and leads to what may be termed a low pressure supply pipe 42. Preferably a steam pipe 43 from the low pressure steam header 28 also leads to the low pressure supply pipe 42, the steam pipe 43 being equipped with a valve 44. A high pressure supply pipe 45 extends from the previously mentioned steam header 11 to the region of the low pressure supply pipe 42, so that both the high pressure supply pipe 45 and the low pressure supply pipe 42 may be utilized to satisfy an outside demand.

The outside demand for steam in the illustrated arrangement is provided by a steam shower or steam spray 47 for moistening a traveling web of paper, such steam consuming devices being well known in the art. The steam shower or spray 47 is fed by a pipe 48 controlled by a valve 50. Since the steam should be supplied to the pipe 48 in a substantially constant manner, a surge tank 51 is provided to smooth out any fluctuations in pressure that may arise from intermittent or varying release of steam, the released steam being fed into the surge tank and being fed therefrom to the pipe 48. The tank 51 also serves as a flash tank.

Preferably, but not necessarily, the steam is delivered to the surge tank 51 by a suitable injector device 52, the detailed construction of which is shown in Fig. 2. The injector device 52 has a jet nozzle 53 fed by the high pressure supply pipe 45 and has the usual annular portion 55 to which the low pressure supply pipe 42 is connected. The annular portion narrows to a throat in the well known manner, so that the jet action has a suction effect on the low pressure supply pipe 42.

The low pressure supply pipe 42 is shown equipped with a check valve 46 to prevent back flow therein, but in some practices of the invention such a check valve is not necessary. For example, if the pressure differential between the steam in the high pressure supply pipe 45 and the low pressure supply pipe 42 is relatively low, or if the injector device 52 adequately compensates for such a pressure differential, the check valve 46 may be omitted.

Suitable valve means is provided to control the flow of steam through the high pressure supply pipe 45 and the low pressure supply pipe 42, and to permit varying the ratio of steam flow through the two pipes. Preferably separate valves are employed for the two pipes, the drawing showing a valve 57 controlling flow through the high pressure supply pipe 45 and a second valve 58 controlling flow through the low pressure pipe 42.

The high pressure valve 47 is shown equipped with a control arm 60 that it is continuously urged toward open position by a suitable helical spring 61. The spring 61 urges the valve arm against a manually operable adjustment screw 62 that is threaded into a fixed support 63. A suitable solenoid 65 is operatively connected to the control arm 60 to cause opening movement of the arm, and when the solenoid is deenergized the spring 61 moves the valve arm toward closed position.

In like manner the low pressure valve 58 has a control arm 66 that is urged by a suitable spring 67 against an adjustment screw 68, the adjustment screw being screw threaded into a fixed support 69. A suitable solenoid 70 is operatively connected to the valve arm 66 to open

the low pressure valve 58, the valve arm being moved toward closed position by the spring 67 when the solenoid 70 is deenergized.

Any suitable means may be employed to control the two valve-actuating solenoids 65 and 70, but I prefer a timer means that will operate the two solenoids in more or less regular cycles. The particular arrangement shown in Fig. 1 involves the use of a timer that includes a rotating disc 72. The disc 72 is made of metal, or at least has a metal surface for the conduction of current, and has on its face a heart-shaped plate 73 of insulating material, the surface of the plate 73 being flush with the face of the disc. The disc 72 is constantly rotated by suitable means, such as a motor 75. The motor 75 may be of the variable speed type controlled by a suitable rheostat 76. For energization the motor 75 is shown connected by two wires 77 and 78 to leads 79 and 80 from a suitable E. M. F. source.

A first brush 82 is in contact with the metal periphery of the rotating disc 72, and a second brush 83 is mounted on a carriage 84 for movement across the face of the disc 72 in a path diametrical with respect to the disc. The carriage 84 is slidably mounted on a guide rod 85 and is controlled by a suitable worm or adjustment screw 87. The adjustment screw 87 is shown journaled in a fixed support 88, and is shown provided with a knurled head 89 for manual operation.

The described arrangement and shape of the insulating plate 73 is such that when the brush 83 is at the center or axis of rotation of the disc 72 the brush is in constant contact with the insulating plate 73 to prevent current flow between the two brushes 82 and 83. On the other hand, when the brush 83 is positioned near the circumference of the rotating disc 72 the brush will remain in constant contact with the metal of the disc so that current may flow uninteruptedly between the two brushes 82 and 83. Between these two extreme positions of the brush 83 is a range of progressively changing positions in which the rotation of the disc causes the path of conduction between the brush 82 and the brush 83 to be alternately opened and closed in repeated cycles. Each cycle has two stages, one stage of current flow, an alternate stage of no current flow, and the ratio of time duration of the two stages varies progressively as the brush 83 is shifted radially outward. When the brush 83 is relatively near the axis of rotation of the disc 72 the closed circuit periods are relatively short and the open circuit periods are relatively long, whereas when the brush 83 is relatively close to the periphery of the disc 72 the periods of current flow are relatively long and the periods of deenergization are correspondingly short.

It is apparent that the rheostat 76 may be adjusted to vary the speed of rotation of the disc 72 and thereby vary the frequency or duration of the cycles of operation. It is further apparent that the knurled head 89 of the adjustment screw 87 may be rotated to vary the relative durations of the two stages in each cycle.

When the rotating disc 72 provides a path for current conduction between the two brushes 82 and 83 a solenoid 65 is energized for opening the high pressure valve 47. The circuit may be traced as follows: wire 96 from the previously mentioned lead 79; the coil of a relay generally designated 91; wire 92; solenoid 65; wire 93; brush 82; metal

disc 72; brush 83; and wire 94 to the second lead 80.

The relay 91 controls a second circuit for energizing the second solenoid 70 for the low pressure valve 58, the arrangement being such that the second circuit is open when the relay is energized and automatically closes whenever the relay is deenergized. This second valve actuating circuit may be traced as follows: wire 96 from the previously mentioned lead 79; solenoid 70; the armature or switch arm of relay 91; and wire 97 to the second lead 80.

Preferably suitable switches are added to the two circuits to permit flexibility in the modes of operation. Thus a switch 95 is shown in series with the solenoid 70 for the low pressure valve 58, and a shunt 98, controlled by a normally open switch 99, is placed across the two wires 92 and 93 of the circuit for the solenoid 65 to permit short circuiting of that solenoid when desired.

The exceptional flexibility of the described system with respect to character of operation may be appreciated by considering the following ways in which the system may be set up for different modes of operation in the practice of the invention.

First mode of operation

In the first mode of operation the valve 44 is closed in the steam pipe 43 and the valve 41 in the steam pipe 36 is opened. Switch 95 is closed and the shunt switch 99 is open. With continuous rotation of the timing disc 72 the circuit for energizing the solenoid 65 to open the high pressure valve 47 is intermittently energized. Such energization causes the high pressure valve 47 to be opened in opposition to the spring 61 and simultaneously causes the second solenoid 70 to be deenergized by the relay 91, thereby to permit the second spring 67 to close the low pressure valve 58. During this stage of each cycle of rotation of the disc 72 steam is supplied to the surge tank 51, primarily if not solely, by the high pressure supply pipe 45, the steam flowing directly from the boiler 10 without passing through any of the heat exchangers. When the circuit for the solenoid 65 is deenergized by the movement of the insulating plate 73 into position under the brush 83, the spring 61 is free to close the high pressure valve 47 and simultaneously the deenergization of the relay 91 causes the circuit to be closed through the second solenoid 70 for opening the low pressure valve 58. During this second stage of the cycle of rotation of the disc 72, steam is supplied to the surge tank 51, primarily if not solely, by the low pressure supply pipe 42.

It is to be noted that there is a clear channel from the boiler 10 through the various drier cylinders 19 and 20 to the surge tank 51 since there are no traps to block steam flow. Because such free communication exists between the boiler 10 and the surge tank 51 by way of the low pressure side of the system, any release of steam to the surge tank by the low pressure valve 58 will substantially increase the velocity of flow through all of the drier cylinders 19 and 20, with consequent increase in the heat output of the system. It is to be further noted that the suction effect of the injector device 52 promotes flow of velocity in the drier cylinders.

Second mode of operation

The second mode of operation is attained by adjusting either the adjustment screw 62 or the 75 adjustment screw 68, or preferably both, the set-

ting being such as to prevent complete closing of the corresponding valves. Whenever one of these adjustment screws prevents complete closing of the operation of the corresponding valve, rotation of the disc 72 will result in periodically changing the rate of flow through the valve. Thus under this second mode of operation there will be continuous but varying flow through the low pressure valve 58 instead of intermittent flow, the flow varying sufficiently to produce the desired pulsating effect in the drier cylinders 19 and 20.

Suppose in this second mode of operation it is desired to increase the rate of steam supply to the steam shower 47 without changing the frequency or quantity of steam released from the low pressure side of the system through the intermittently operated low pressure valve 58. To accomplish this purpose it is merely necessary to change the adjustment of the screw 62 to prevent complete closing of the high pressure valve 47 when the solenoid 65 is deenergized, whereby the total volume of steam supplied from the high pressure side of the system to the high pressure valve 47 will be increased.

Suppose, on the other hand, it is desired that the amount of steam released on the low pressure side of the heating system be varied without substantial change in the overall or average rate of steam supply to the steam shower 47. This purpose may be accomplished by adjusting the screw 68 that limits the closing action of the valve 58 and oppositely adjusting the screw 62 for the valve 47. This second purpose may also be accomplished by introducing adjustment of the screw 87 that determines the position of the brush 83. Changing the position of the brush 83 will increase or decrease the duration of the periods in which the solenoid 70 is energized, and any further adjustment necessary to avoid changing the total volume of flow to the steam shower 47 may be accomplished by manipulating one or both of the adjustment screws 62 and 68.

Third mode of operation

The third mode of operation consists of modifying either of the first two described modes of operation by closing the valve 41 and opening the valve 44. The result of this valve change is to cause the effect of the release of steam through the low pressure valve 58 to be concentrated on the drier cylinders 19 of the first bank A with respect to flow promotion, the second bank of drier cylinders 20 being cut off from the effect of releasing steam on the low pressure side of the system.

Fourth mode of operation

In the fourth mode of operation the system is set up as described under the first mode of operation, but the switch 95 is opened to keep the solenoid 70 deenergized so that the low pressure valve 58 is not responsive to rotation of the disc 72. The screw 68 associated with the low pressure valve 58 is adjusted to maintain the valve constantly open to a desired degree, so that steam is continuously released from the return side of the system to the surge tank 51. The rotation of the disc 72, however, causes opening and closing of the high pressure valve 60 in regular cycles, so that high pressure steam from the high pressure supply pipe 45 is intermittently or variably released to the surge tank 51. During each of the short periods of steam release from the high pressure supply pipe 45 the suction effect of the injector device 52 accelerates flow through the low

5 pressure supply pipe 42 and causes momentary reduction of pressure in the steam separator 35. Thus the intermittent release of steam from the high pressure supply line 45 results in pulsations in all of the drier rolls 19 and 20 in the heating system.

Fifth mode of operation

To change from the fourth mode of operation described above to the fifth mode of operation the switch 95 is closed and the shunt switch 99 is closed. The closing of the shunt switch 99 short circuits the solenoid 65 to make the high pressure valve 47 non-responsive to rotation of the timer disc 72, but the closing of the switch 95 makes the solenoid 70 responsive to the rotation of the disc. It is apparent that the low pressure valve 58 is now opened intermittently to release steam to the surge tank 51, thereby causing pulsating flow throughout the drier rolls 19 and 20. The adjustment screw 62 may be positioned to permit the high pressure valve 47 to be constantly closed, or may be positioned to permit a certain amount of continuous flow through the high pressure valve. Any flow whatsoever through the high pressure valve will, by virtue of the suction effect of the injector device 52, tend to promote flow through the steam system whenever the low pressure valve 58 is opened in the repeated cycles of rotation of the disc 72.

Sixth mode of operation

In the sixth mode of operation the system is set up as described under the first mode of operation, but the adjustment screws 87 for controlling the position of the brush 83 is moved to one of its extreme positions or the other to cause constant energization of one or the other of the solenoids 65 and 70 to permit release of steam solely from one or the other of the valves 47 and 58 in a constant manner. This mode of operation may be used temporarily for some special reason.

Seventh mode of operation

In the seventh mode of operation the electrical arrangement for energizing the solenoids 65 and 70 is deenergized so that the positions of the low pressure valve 58 and the high pressure valve 47 will be determined solely by adjustment of the corresponding screws 68 and 62. The adjustment of the two valve controlling screws is such as to permit one or both of the valves to release steam continuously to the surge tank 51. If both valves are opened the suction effect created by the injector device 52 will substantially increase the velocity of flow through the various drier cylinders 19 and 20.

It will be readily appreciated that the described arrangement for controlling the release of steam from the high pressure and low pressure sides of a steam heating system, or any other arrangement of the same general character, may be used to supply any steam-consuming device with steam from the heating system with consequent promotion of flow through the heating system. The outside demand may be the requirement of steam to heat water, the requirement of steam for circulation through coils to heat air, et cetera. In the claims the phrase "a substantially clear channel" is to be taken as meaning a channel providing sufficient freedom of communication therethrough to cause velocity responses to the release of steam therefrom.

It is apparent that the invention may be practiced with pulsating intermittent release of steam in which it is contemplated that there will be a

complete cessation of steam release between pulsations, and that the invention may be practiced with pulsating continuous release in which the rate of flow varies between positive values. In either of these practices the frequency of the consequent variations in pressure in the steam will be sufficiently high to reap the advantages in lowered thermal resistance at the heat exchangers that are explained in the previously mentioned co-pending Harrison et al. application.

It is also to be noted that the described system in some practices of the invention may operate without substantial or even significant pulsations, the two valves serving solely as means to apportion the derived steam between the two channels.

The description herein in specific detail of a preferred embodiment of the invention will suggest to those skilled in the art various changes and substitutions under the basic concept, and the right is reserved to all such departures from the disclosure that lies within the scope of the appended claims.

I claim as my invention:

1. In a steam system including a steam source, a heat exchanger connected thereto with a substantially clear channel from the steam source through the heat exchanger, and a steam consuming device, the combination therewith of means to create pulsating steam flow through said heat exchanger for increased heat output by the heat exchanger, said means comprising a first passage means from said channel on the low pressure side of the heat exchanger to said device to promote steam flow through the heat exchanger and to satisfy a fraction of the steam demand of the device, a second passage means from said steam source to said device to satisfy the remainder of the steam demand of the device without substantial effect on the steam flow through the heat exchanger, and means controlling flow through said two passage means in continually repeated cycles of two stages, one stage in which said steam demand is satisfied primarily by said heat exchanger through said first passage means and one stage in which said steam demand is satisfied primarily by said source through the other of said passage means, whereby the velocity of steam flow through said heat exchanger is continually varied in a pulsating manner.

2. In a steam system a combination as set forth in claim 1 which includes adjustable means to vary the frequency of said cycles, thereby to vary the frequency of the flow pulsations.

3. In a steam system a combination as set forth in claim 1 which includes means to vary the relative durations of said two stages in a cycle.

4. In a steam system a combination as set forth in claim 1 which includes means to vary the magnitude of steam flow in at least one of said passages in at least one of said stages.

5. In a steam system including a steam source, a heat exchanger connected thereto with a substantially clear channel from the steam source through the heat exchanger, and a steam consuming device, the combination therewith of means to create pulsating steam flow through said heat exchanger for increased heat output by the heat exchanger, said means comprising a first passage means from said channel on the low pressure side of the heat exchanger to said device to promote steam flow through the heat exchanger and to satisfy a fraction of the steam demand of the device, a second passage means from said steam source to said device to satisfy

the remainder of the steam demand of the device, without substantial effect on the steam flow through the heat exchanger, two valve means for said two passage means, respectively, said two valve means being interlocked for opening movement of the two valve means alternately, and means to operate said two valve means repeatedly for pulsating variation in the rate of flow through said heat exchanger without corresponding variation in the rate of flow to said device.

6. In a steam system including a steam source, a heat exchanger connected thereto with a substantially clear channel from the steam source through the heat exchanger, and a steam consuming device, the combination therewith of means to create pulsating steam flow through said heat exchanger for increased heat output by the heat exchanger, said means comprising a first passage means from said channel on the low pressure side of the heat exchanger to said device to promote steam flow through the heat exchanger and to satisfy a fraction of the steam demand of the device, a second passage means from said steam source to said device to satisfy the remainder of the steam demand of the device, said two passage means cooperating to form an injector means whereby the flow of steam through said second passage means increases the velocity of flow through said first passage means, and means to vary the rate of flow through said first passage means in a pulsating manner thereby to continually vary the rate of flow through said heat exchanger in a pulsating manner.

7. In a steam system including a steam source, a heat exchanger connected thereto with a substantially clear channel from the steam source through the heat exchanger, and a steam consuming device, the combination therewith of means to create pulsating steam flow through said heat exchanger for increased heat output by the heat exchanger, said means comprising a first passage means from said channel on the low pressure side of the heat exchanger to said device to promote steam flow through the heat exchanger and to satisfy a fraction of the steam demand of the device, a second passage means from said steam source to said device to satisfy the remainder of the steam demand of the device without substantial effect on the steam flow through the heat exchanger, means controlling flow through said two passage means in repeated cycles of two stages, one stage in which said steam demand is satisfied primarily by one of said passage means and one stage in which said steam demand is satisfied primarily by the other of said passage means whereby the velocity of steam flow through said channel is continually varied in a pulsating manner, and a surge tank in communication with said two passage means to minimize pulsations in the flow of steam to said device.

8. In a steam system having a heat exchanger and a steam consuming device discharging steam into substantially atmospheric pressure the combination therewith of means to supply said device with steam and at the same time to create pulsating flow in said heat exchanger to attack the gas and condensate films in the heat exchanger, said means comprising a first passage means to supply steam to said device from the low pressure side of said heat exchanger, thereby to promote flow through the heat exchanger, a second passage means providing communication from another part of the steam system to said device to supply steam to the device, and con-

tinually operating valve means to open and close said two passage means alternately to cause pulsating flow in said heat exchanger without interrupting the supply of steam to said device.
